(57) **CLAIM**

The ornamental design for a wallet, as shown and described.

DESCRIPTION

FIG. 1 is a perspective view of a wallet design showing my new design.

FIG. 2 is a front view of the wallet.

FIG. 3 is a rear view of the wallet.

FIG. 4 is a left view of the wallet.

FIG. 5 is a right view of the wallet.

FIG. 6 is a top view of the wallet.

FIG. 7 is a bottom view of the wallet; and,

FIG. 8 is a perspective view of the wallet in the closed state. The broken lines in the drawings depict portions of the wallet that form no part of the claimed design.
